(57) CLAIM

The ornamental design for an underwear garment, as shown and described.

DESCRIPTION

FIG. 1 is a perspective view of an underwear garment;

FIG. 2 is a front side view thereof;

FIG. 3 is a back side view thereof;

FIG. 4 is a left side view thereof; and,

FIG. 5 is a right side view thereof.

The broken lines in the drawings depict portions of the underwear garment that form no part of the claimed design.
